POWER WHEEL

Julius E. Carlin, Freehold, N. J.

Application October 1, 1936, Serial No. 103,484

8 Claims. (Cl. 170—10)

This invention relates to power means. More particularly, it relates to power wheels provided with highly improved vane construction.

One of the objects of this invention is to provide a power wheel of the character described having conical shaped vanes of maximum capacity, so that the difference in power pressure will always be in favor of the concavity as against the convexity.

10 Another object of my invention is to provide a power wheel of the character described, which is adapted to be used for windmills and in which the construction and disposition of the vanes are such that the tail, which is customarily employed in windmill wheels, may be dispensed with.

A further object of my invention is to provide a power wheel vane construction which may be easily applied to old windmills now in use, to render them much more efficient.

20 A still further object of my invention is to provide a power wheel construction of the character described, in which a plurality of such wheels may be utilized for building up great power.

A still further object of my invention is to provide a power wheel of the character described which comprises comparatively few and simple parts, which is easy to assemble and relatively inexpensive to manufacture, and which at the same time operates with a maximum degree of efficiency.

30 Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible embodiments of this invention,

Fig. 1 is a diagram illustrating a method of constructing the conical shaped vanes, whereby the maximum capacity of the cone is obtained;

45 Fig. 2 is a side elevational view of a power wheel embodying my invention, mounted for rotation on a horizontal axis;

50 Fig. 3 is a side elevational view, partly sectional, of a power wheel similar to that illustrated in Fig. 2, but mounted for rotation on a vertical axis;

Fig. 4 is a plan view of a power wheel similar to Fig. 2 but illustrating a modified form of mounting for the vanes;

55 Fig. 5 is a side elevational view of the Fig. 4 form of device;

Fig. 6 is still another modified form of power wheel construction embodying my invention; and

Fig. 7 is still another modified form of construction of a power wheel adapted for use in connection with windmills.

Referring now in detail to the drawing, there is disclosed in Fig. 2 one form of power wheel construction embodying my invention, comprising a wheel 10 which may be of any suitable construction generally employed in power wheels, and mounted on a horizontal shaft 11 for rotation therewith. Also mounted on the shaft 11 is a pulley 12 having a belt 13 mounted thereon, said belt 13 being also mounted on another pulley not shown, which may be mounted on a shaft to be used for the purpose of driving any desired mechanism. Mounted on the rim 10a of the wheel 10 there is provided a plurality of vanes 15. These vanes are preferably of conical shape, as shown, and mounted on said wheel 10 by having one flat side 15a thereof fixed to said rim 10a by any suitable attaching means, such as, for example, screws 16. The cone shaped vanes 15 are so constructed that they will be of maximum capacity.

A method of constructing such cones is illustrated in Fig. 1 where there is shown a circular piece of suitable material 20 from which a sector xyz is cut, the distance P being substantially equal to the radius R. The ends xy and xz are then brought together and fastened in any suitable manner to produce a cone 15, which is of maximum capacity. That the cone so produced will be of maximum capacity is illustrated by the following calculations:

20 Referring to Fig. 1 of the drawing, let R be the radius of the circular disk 20, xyz the sector to be cut out so that the remainder of the disk may be made into a conical vane by fastening the edges xy and xz together. Let r be the radius of the conical vane, h its perpendicular height, L its slant height and yz the arc of the sector xyz.

25 Then L is obviously equal to R. $2\pi R - yz = 2\pi r$ or the arc $yz = 2\pi(R - r)$. Also

$$h = \sqrt{L^2 - r^2} = \sqrt{R^2 - r^2}$$

30 V, the volume of the conical vane equals

$$\frac{\pi r^2 h}{3} = \pi r^2 \frac{\sqrt{R^2 - r^2}}{3}$$

35 Differentiating with respect to r, we get

$$\frac{dV}{dr} = (\pi r^2) \left(\frac{-r}{3\sqrt{R^2 - r^2}} \right) + \frac{2\pi r}{3} \sqrt{R^2 - r^2} = \frac{2\pi r(R^2 - r^2) - \pi r^3}{3\sqrt{R^2 - r^2}}$$

5

10

15

20

25

30

35

40

45

50

55

Putting the last term of the equation=0 for maximum or minimum, we have

$$2\pi r(R^2-r^2)-\pi r^3=0,$$

and

$$5 \quad r=R\sqrt{\frac{2}{3}}$$

Therefore, the arc

$$10 \quad yz=2\pi(R-r)=2\pi\left(R-R\sqrt{\frac{2}{3}}\right)$$

and when reduced, the arc yz =approximately

$$\frac{23R}{20}$$

- 15 When the edges xy and xz are fastened upon each other, the open conical vane or cone so formed will thus be of maximum capacity.

The apex angle of the cone of maximum capacity may be readily computed. Thus, when the 20 arc P

$$\left(\text{equal to } \frac{23}{20} \text{ of } R\right)$$

is removed from the circular disc and the edges 25 xy and xz are brought together, the circumference of the base of the cone thus formed will be substantially equal to

$$2\pi R - \frac{23}{20}R$$

- 30 or $R(2\pi - 1.15)$ where R is the original radius of the disc and therefore the slant height of the formed cone. The radius of the base of the cone, conveniently denominated as R' , is equal to the circumference of the base divided by 2π .

$$35 \quad \text{or } R' = \frac{R(2\pi - 1.15)}{2\pi}$$

Giving π its value, $R' = 0.819R$.

The apex angle is twice the angle included 40 between the slant height and the axis of the cone and as the axis and base radius of the cone form two sides of a right angle triangle of which the slant height is the hypotenuse, the apex angle equals twice the angle whose sine is

$$45 \quad \frac{R'}{R}$$

Therefore, the apex angle equals twice the angle whose sine is

$$50 \quad \frac{0.819R}{R} \text{ or } 0.819$$

That is, the apex angle is equal to 110° .

It is thus seen that by having conical shaped 55 vanes 15 constructed in accordance with the above described manner, when any source of energy is applied to the wheel 10 , such as water, steam or air pressure, the difference in such pressures between the concave and convex surfaces of the 60 cone will always be in favor of the concavity as against the convexity. This will cause the wheel 10 to rotate in one direction only, as indicated by the arrow D in Figs. 2 and 3 of the drawing.

In Fig. 3 I have shown a power wheel 10 and 65 vanes 15 similar in construction and operation to that illustrated in Fig. 2, but with the wheel 10 being mounted on a vertical shaft $11a$ for rotation therewith about a vertical axis instead of on a horizontal axis as in the Fig. 2 form.

In Figs 4 and 5 I have shown a modified form 70 of power wheel construction in which I prefer to mount the cones 15 on the flat side of the periphery of the wheel 10 rather than on the rim $10a$. One advantage of the construction illustrated in Figs. 4 and 5 is to be found in the fact that it is

possible thereby to construct a wheel having a much smaller outside diameter than could be done with the form shown in Fig. 2. Another advantage of the Figs. 4 and 5 form of construction lies in the fact that all the vanes are exposed to the action of the source of power at the same time, thereby obtaining increased power.

If it is desired to use the forms of my invention illustrated in Figs. 2, 4 and 5 for windmill operation, they may be efficiently employed in cooperation with the type of tail customarily employed in windmills.

In Fig. 6 I have illustrated another modified form of my invention, in which a plurality of power wheels 10 having conical shaped vanes 15 of similar construction to those shown in Figs. 2, 3 and 4 are mounted on a vertical shaft $11b$ for rotation therewith. The power generated by the wheels 10 and transmitted to the shaft $11b$ will be cumulative, and thus, it is possible by this 20 type of construction to build up great power, if desired.

In Fig. 7 I have shown still another modified form of my invention adapted for use in connection with wind power of the type commonly employed in windmills. In this form of construction I prefer to mount a power wheel $10c$ on a split shaft $11c, 11e$ for rotation about a horizontal axis. The power wheel $10c$ may be of a construction similar to that shown in Figs. 4 and 5; 30 that is, with the vanes 15 mounted on a flat side of said wheel. Instead of the tail customarily employed in windmills, I mount another power wheel $10d$, similar in construction and arrangement of vanes to the Fig. 2 form, on a shaft $11d$ 35 for rotation about a horizontal axis at right angles to the axis of rotation of the wheel $10c$. The wheel $10d$ is preferably of imperforate construction so that it may effectively act as a tail vane. The wheels $10c$ and $10d$ may be pivotally mounted 40 to rotate as a unit about a vertical axis, by means of a bearing support 23 , in which the shafts $11c, 11d$ and $11e$ may be journaled, the portion of the shaft $11e$ being journaled in the bearing portion 25. Suitable gearing means 22 is provided to permit the rotation about a vertical axis of the support 23 carrying the wheels $10c$ and $10d$. When the wind blows in a direction shown by the arrow, the wheel $10c$ will rotate with the shaft $11c$ in a clockwise direction to cause the shaft $11f$ to 50 rotate in a counter-clockwise direction by means of the gears 22 . At the same time, due to the fact that the wheel $10c$ is of lesser diameter than the wheel $10d$, the wind passing by said wheel will actuate the vanes 15 of the wheel $10d$ to 55 cause counter-clockwise rotation of said wheel about the shaft $11d$. Mounted on the shaft $11d$ is a bevel gear 20 adapted to mesh with a bevel gear 21 on the shaft $11e$. It is thus seen that when the wheel $10d$ rotates in a counter-clockwise 60 direction, it will cause the shaft $11f$ to also rotate in a counter-clockwise direction, which is the same direction of rotation of the shaft $11f$ as that caused by the rotation of the wheel $10c$ on the shaft $11c$. It is thus seen that the power 65 of the wheels $10c$ and $10d$ transmitted to the shaft $11f$ are additive, to provide a highly efficient windmill. Power may be taken off from the shaft $11f$ to operate any desirable mechanism or mechanisms, in any suitable manner.

It is thus seen that by this form of construction, the wheel $10d$ is adapted to act as a tail to align the wheel $10c$ and at the same time is made use of to generate additional power.

While in the drawing there has been illustrated 75

a type of power wheel particularly adapted for use with wind power, it is understood, however, that my invention may be applied to the use of power wheels operated by water, steam or air power.

It will thus be seen that there is provided a device in which the several objects of this invention are achieved, and which is well adapted to meet the conditions of practical use.

10 As various possible embodiments might be made of the above invention, and as various changes might be made in the embodiments above set forth, it is to be understood that all matter herein set forth or shown in the accompanying drawing 15 is to be interpreted as illustrative and not in a limiting sense.

Having thus described my invention, I claim as new and desire to secure by Letters Patent:

1. A power device of the character described 20 comprising a rotatably mounted vertical shaft, a plurality of wheels mounted on said shaft for rotation therewith, said wheels being disposed on different planes, each of said wheels having mounted thereon for rotation therewith a plurality of circumferentially spaced cone-shaped 25 vanes, the axis of rotation of said vertical shaft being substantially at right angles to the direction of application of power.

2. In a windmill, in combination, a horizontal 30 rotatably mounted shaft, a power wheel mounted on said shaft for rotation therewith, a second horizontal rotatably mounted shaft at right angles to said first shaft, a second power wheel mounted on said second shaft for rotation therewith, a unitary support for said shafts, said support being pivotally mounted for rotation about a vertical axis, means for driving said power 35 wheels, and means for transmitting the power generated by one of said wheels to a third rotatably mounted shaft.

3. In a windmill, in combination, a horizontal 40 rotatably mounted shaft, a power wheel mounted on said shaft for rotation therewith, a second horizontal rotatably mounted shaft at right angles to said first shaft, a second power wheel

5 mounted on said second shaft for rotation therewith, a unitary support for said shafts, said support being pivotally mounted for rotation about a vertical axis, means for driving said power wheels, and means for additively transmitting the power generated by both of said power wheels to a third rotatably mounted shaft.

4. In a windmill, in combination, two rotatably mounted power wheels adapted to rotate on horizontal axes at right angles to each other, one of 10 said power wheels being so constructed and arranged that it is adapted to be used as a tail, means for driving said power wheels, and means for additively transmitting the power generated by both wheels to operate a mechanism.

5. In a windmill, in combination, two rotatably mounted power wheels adapted to rotate on horizontal axes at right angles to each other, one of 15 said power wheels being so constructed and arranged that it is adapted to be used as a tail, 20 means for driving said power wheels comprising a plurality of cone-shaped vanes rigidly mounted directly on said wheels, and means for additively transmitting the power generated by both wheels to operate a mechanism.

6. A power wheel of the character described 25 comprising a rotatably mounted wheel and a plurality of hollow cone-shaped vanes of maximum capacity fixed to said wheel for rotation therewith, the circumference of the base of said cone-shaped vanes being about $R(2\pi - 1.15)$ where R 30 is the slant height of said vanes.

7. A power wheel of the character described 35 comprising a rotatably mounted wheel and a plurality of vanes fixed to said wheel for rotation therewith, said vanes being cone-shaped and having an apex angle of about 110° whereby they will be of maximum capacity.

8. A power wheel of the character described 40 comprising a rotatably mounted wheel and a plurality of hollow cone-shaped vanes fixed to said wheel for rotation therewith, each of said vanes having a maximum capacity for its surface area.

JULIUS E. CARLIN.
